MACHINE FOR TEARING WOVEN FABRIC

Maynard W. Higby, Utica, N. Y.

Application September 24, 1943, Serial No. 503,715

11 Claims. (Cl. 164—84.5)

My present invention relates to a machine for tearing crosswise fullwidth woven fabric.

The main purpose of this invention is to provide a new and improved machine for tearing crosswise an indefinitely long strip of woven fabric into pieces of the desired length that will be true or straight at the new ends; that is, will be torn following a thread of the filling as the housewife would say but literally torn across between adjacent filling threads so that a hem made at the end will be straight across when laundered as usual. It has long been recognized that woven fabric such as used for sheets, pillow cases, and window shades and several other purposes is crooked when it comes from the finishing machine; that is the filling threads curve forward or backward relative to a line straight across at right angles to the length of the fabric.

The known remedy for this trouble has been to tear the fabric across following a filling thread. This tearing operation has long been done by a hand operation. While some machines have been devised to do this, they are apparently not acceptable to the manufacturers of sheets, etc., for the hand tearing continues to be used at great expense and sometimes with delay to production for it takes several men to do the necessary tearing in a plant producing a considerable quantity of sheets per day.

The purpose of my invention is to provide a machine that will be well capable of performing the operation satisfactorily and regularly and with a minimum of supervision and with a speed such that one or at least a few machines will do the work for a large plant and thus save the labor of several men.

Other purposes and advantages of my invention will appear from the specification and claims hereinafter set forth.

It is the main purpose of my invention to provide a tearing machine of the type described where the tearing device per se comprises a relatively small spear point adapted to be moved vertically against a tautly held section of the full width fabric intermediate its opposite edges while a pair of loosely mounted slanting tearing arms actually tear the fabric from the small puncture made by the spear point clear through the fabric and through its opposite edges following the curve of the cross threads or woof from the spear incision. This secures the desired straight end edges for the sheets or other articles to be made from the fabric but leaves the oncoming end of the long length of fabric completely separated

from the fabric carrying means beyond the tearing zone.

A further purpose of my invention is to provide auxiliary feeding means, usually herein called catch belts capable of picking up the oncoming loose end and carrying it through the second pair of holding members (usually hereinafter for brevity called jaws) and into the necessary engagement with the main carrying means beyond the tearing zone and beyond the second pair of fabric engaging jaws.

A still further purpose of my invention is to provide these auxiliary feeding means in the form of two separate longitudinally extending sets of endless belts each belt carried on a pair of pulleys, the two pulleys for each belt being mounted on a carriage movable longitudinally of the machine so that after each tearing operation the two sets of auxiliary feed belts will move towards each other and preferably somewhat past each other and into the tearing zone and re-establish the engagement of the oncoming end with the later-reached main feeding means and before the next tearing operation the auxiliary feeding belts will be moved away from each other and out of the way of the vertically operative tearing means.

Fig. 1 is a vertical longitudinal sectional view on a small scale on line 1—1 of Fig. 4 of a machine embodying my invention for tearing desired lengths of material from a long strip of woven fabric, the tearing device itself being in raised or inoperative position and the "catch belts" or auxiliary feeding means being in separated or retracted position ready for the tearing device itself to descend and operate, both pairs of jaws also being closed upon the fabric.

Fig. 2 is a partial view like Fig. 1 after the tearing device has operated and been raised but while the two pairs of jaws are still closed but before the "catch belt" carriers have been advanced to carry the new end of fabric past the tearing zone to the second pair of jaws and the adjacent conveyor means.

Fig. 3 is a partial view similar to Figs. 1 and 2 but after the tearing device has descended and also ascended and showing the two sets of "catch belts" advanced to pick up the new oncoming severed end of the fabric, the jaws being now opened.

Fig. 4 is a transverse vertical section on an enlarged scale of my machine on line 4—4 of Fig. 1 showing in full lines the tearing device in raised position and showing in dash lines said tearing device in lowered position, the fabric holding jaws

of the machine being shown in separated position as when the fabric is being fed forward.

Fig. 5 is a horizontal sectional view on line 5—5 of Fig. 1 of the central part of my machine omitting the fabric to be torn but showing in plan view the regular feed belts for advancing the woven fabric to be torn and showing the "catch belts" in distended position.

Fig. 6 is a view similar to Fig. 5 but on line 6—6 of Fig. 3 viz. the plane of the top of the fabric showing the two sets of "catch-belts" advanced to catch and carry forward the new severed end of the fabric.

Fig. 7 is a side elevation of one of the "catch belt" carriages with a catch belt on its rollers and below the carriage an adjacent portion of the platform carrying this set of "catch belt" carriages.

Referring to the drawings in a more particular description it will be seen that as best seen in Fig. 4 the tearing device per se of my invention comprises a small spearpoint 20 at the bottom end of a vertically mounted and vertically moved spear-carrying rod 21 which spearpoint has attached thereto at its opposite sides two loosely mounted tearing arms 22 which extend upwardly and crosswise of the therebelow intermittently progressed and stationary fullwidth length 23 of said woven fabric.

The lower end of each of these arms 22 is loosely hinged to its wing of the spearpoint 20 and the upper end of each arm is loosely connected to the outer end of a brace 24 which in turn has its inner end attached somewhat loosely to a crosshead 25 on the upper part of the said vertical spear-carrying rod 21. The middle part of the said rod 21 is operatively connected to the lower end of a pitman 26 the other end of which is pivotally attached to the crank arm 27 preferably provided on a wheel 28 suitably mounted the proper distance above the said length of fabric to be operated upon and preferably on a horizontal shaft 29 extending longitudinally of the said length 23 fabric and of the machine which progresses and tears said fabric. Two eyes 30 and 31 encircling respectively the upper part and the lower part of the said spear-carrying rod, guide said rod in a vertical path but the said loose mounting of the side arms allows the side arms to move the necessary amount back or forward to follow the bow or crosswise curve of the fabric when the rotation of said wheel 28 drives the spear point 20 down into the middle portion of the short length of fabric 23a temporarily held in the tearing zone of the machine and makes a short initial cut crosswise and the slanting arms 22 at once with a camming action tear the fabric in opposite directions completely across to and through its selvaged edges.

As the means for temporarily holding the short length 23a of fabric stationary and taut in the tearing zone I provide two spaced pairs of jaws, jaw 32 being the upper and jaw 33 being the lower and cooperating jaw of the pair of jaws first reached by the advancing fabric (said first pair being to the right as the machine is shown in Fig. 1) and jaw 34 being the upper jaw and jaw 35 being the lower jaw cooperating therewith of the second reached pair of jaws, the second pair being in practice a few inches beyond the first pair so as to allow room for the tearing device to descend between said two pairs of jaws with its arms 22 swinging to follow the bow of the fabric and also to allow for the presence

therebetween of parts of the "catch belts" hereinafter described.

The shaft 29 for wheel 28 is carried in a cross bar 36 which bar also carries the motor 37 and reducing gear or other mechanism for driving at a relatively slow speed the wheel 28 which intermittently moves the tearing device. The said cross bar 36 is a part of an upright rear frame having spaced side posts 38 and 39 upstanding from and past the horizontally extending spaced side rails 40. Upon these rear upright posts are mounted in moveable relation to each other the said second reached or rear pair of jaws 34 and 35 preferably by having the upper jaw 34 fixed to the said posts and by having the lower jaw 35 slidable in or on the said posts.

A front upright frame has upright posts 41 rising from or past said side rails 40 and connected by a top crossbar (carrying the top guide eye 30) and connected by a lower crossbar viz. the upper front jaw 32 carrying the said lower guide eye 31 for guiding the spear-carrying rod 21.

In or upon the opposite side rails 40 of the machine are located oppositely disposed pairs of bearings for the fabric supporting rollers 45. As already mentioned, this machine is organized and illustrated to have the long length of woven fabric 23 moved from the right-hand half of the machine towards the left and through the first pair of jaws 32 and 33. Accordingly a roller 45 is located just to the right of this first pair of jaws and another roller 45 is located as far as required to the right so that these two rollers may have mounted thereover several endless bands of webbing 46, the upper length of which travels to the left and over the roller 45 which is located near but to the right of the first-reached pair of jaws. Preferably this roller is the one which is provided with a pulley 47 driven by power from any convenient source whereby in obvious manner the several belts of the webbing 46 are caused to move to the left and thereby move the length of woven fabric that is rested upon said belts of webbing. As shown more or less diagrammatically in Fig. 1 to the right of the right-hand roller 45, there is a feed table 44 leading to the belts 46 and to this table the woven fabric is delivered by means of two cooperating oppositely driven friction rollers 48 and 49 which it is assumed are drawing the woven fabric from a source of supply such as a large roll of the fabric or even from the adjacently located finishing machine of the plant for separately finishing indefinitely long lengths of woven fabric.

Beyond or to the left of the left-hand pair of fabric-engaging jaws 34 and 35 there is located roller 50 and spaced further to the left upon the side rails of the machine is a similar roller (not shown). Over these rollers are stretched several endless belts 51 of webbing for moving the severed fabric to the left from the feed jaws 34 and 35. One of these last-named rollers will be rotated by suitable power so as to impart a forward motion (or to the left as this machine is illustrated) to the several belts 51 stretched over this left-hand series of rollers.

At any convenient part on the receiving or right-hand length of travel of the woven fabric, there is located a cloth measuring meter 52 having a suitable friction-surfaced fabric-engaging wheel which upon being rotated a suitable number of times measures the length of said woven fabric that is to be cut off as for forming a sheet. This machine can be adjusted to measure the de-

sired number of inches as required for standard sized sheets such as 90 inches, 99 inches or 108 inches. When the contact wheel 17 of said meter 52 has made the proper number of rotations to have passed therebeneath a given length of the fabric for which it is set, an electric contact for the necessary time is made at 78 which by suitable wiring 79 and 80 renders operative the motor 37 which operates the tearing device. At the same time the moveable lower fabric-engaging jaws 33 and 35 are moved so as to close the two pairs of fabric-engaging jaws, through the circuit being completed at 78 through wires 79 and 80 to actuate a solenoid 81 to turn on the compressed air at valve 82 and admit air to the lower half of cylinder 53 through compressed air line 86. After the electric contact member at 78 has remained in contact long enough to complete the tearing operation and return the wheel to its original position, the turning off of the electric current allows return spring 84 to reverse the position of the air valve 82 whereupon air is admitted through air line 85 to the upper ends of the four cylinders 53, quickly causing the pistons 54 to move down and open the lower jaws 33 and 35.

As convenient means for so closing both said pairs of jaws there is provided under the opposite ends of each of said lower jaws a cylinder preferably pneumatic 53 suitably supported in proper position by or from the adjacent side rail 40 and having a piston 54, the piston rod 55 of which extends out from the cylinder and is connected directly to the adjacent end of said lower fabric-engaging jaw. By the admission of air to the lower side of said pistons under pressure, the said two pistons connected to each of said lower jaws will be quickly and simultaneously raised. The valves for admitting such air under pressure to these cylinders will be operated by proper mechanical or pneumatic or electrical means contemporaneously with the actuation of the fabric-tearing device or perhaps a fraction of a second earlier so that by the time the spearpoint 20 descends a short distance towards the short length of fabric 23a between the said two pairs of jaws, said jaws will be closed and the short length of fabric reaching from one pair of jaws to the other will be held taut by said closed jaws and as already stated the spearpoint will make a very short preliminary cut transversely of the fabric and this cut will be quickly continued by the tearing downward travel of the tearing arms 22. After these tearing arms have torn the held length of fabric completely through the selvages at the opposite sides of the fabric, the following half rotation of the wheel 28 will lift the tearing device upwardly entirely clear from between the two pairs of jaws more or less to the position shown by solid lines in Fig. 4 and simultaneously the lower jaws will be moved downwardly to open both pairs of jaws, since the requirement of holding the fabric has now passed. This opening of the jaws will be produced by admitting air to the upper side of the pistons 54 in all four cylinders 53.

From an inspection of Fig. 2 it will be seen that after the cloth-tearing device has descended and performed its complete active operation and then ascended to be out of the way, there are two new ends of fabric 56 and 56' hanging down from the fabric-engaging jaws. Any forward movement by either set of main feed belts that is to the right of the tearing zone or even to the left of the tearing zone will not operate to carry the torn on-

coming end 56 of the fabric just to the right of the severing zone over towards the main delivery belts 51 on rollers 50. It is true that upon the opening of the rearward jaws 34 and 35, the main belts 51 will draw through the feed jaws and move to the left on auxiliary feed belts 64 the piece of fabric 56 that had just been released by said pair of jaws, but the other rollers 45 with their belt 46 on the other or right-hand side of the machine will not be able to carry the severed end 56 up to the jaws 35 and 34 and onto the main belt 51 at that end of the machine. To overcome this very troublesome situation due to the length of woven fabric being entirely severed, I have provided two sets of auxiliary feed belts or what I have called "catch belts". These belts are short endless belts, one set 57 extending through the space between the right-hand jaws 32 and 33 and over the main roller 45 just to the outside of said jaws. An examination of Fig. 7 will best show the construction of one of the catch belt carriages as seen in side elevation while Figs. 4 and 5 show plan views of several of these catch belt carriages. The catch belt 57 is mounted on two spaced-apart rollers 58 which are mounted severally on a short pin that is in the upper ends of two thin arms 60 which have their lower ends fixedly mounted upon the carriage 61. The arms 60 as shown best in Fig. 7 slant away from each other as they go up for a purpose hereinafter mentioned. The catch belt 57 has its upper length extending between the opposite faces of the first pair of jaws 32 and 33 while the lower length of said catch belt passes beneath the lower jaw 33. Several of these catch belts are arranged in the width of the machine with the belts arranged in the spaces between the main feed belts 46 as best shown in Figs. 4 and 5 of the drawings. These catch belts do not have a separate means for driving them but through their contact with the closely located roller 45 just to the right of the right-hand pair of fabric-engaging jaws 32 and 33 these small belts are driven with strength and power enough for the very small-power consuming job which they have. In cross section these belts may be like the common V-shaped belts and rollers 58 may have a V-shaped groove in their peripheries for more readily holding the belts in place and performing their work.

So that the closing of the jaws will not be prevented by these catch belts, notches or recesses 62 on the upper side and 63 on the lower side of the lower jaw 33 will be provided as will be plainly seen on examination of Figs. 2 and 4. The right-hand catch belt carriage 61 places its left-hand pulley 58 inside of the fabric-engaging jaws 32 and 33 while its other pulley 58 is a little distance away from the main belt roller 45 to the outside of said fabric-engaging jaw. A similarly constructed and arranged set of catch belts 64 are provided, mounted upon spaced pulleys 65 and 66 respectively to the outside of, and inside of the left-hand jaws 34 and 35 with its belt passing around the rollers 50 of the main belt system on that end of the machine and with the belt 64 at its upper reach passing between the top of the lower jaw 35 and the bottom of the upper jaw 34.

The lower reach of said catch belt passes below the lower jaw 35 and said jaw has clearance spaces 62 and 63 in its upper and lower edges as already mentioned with respect to lower jaw 33 to allow the jaws to be closed without interference with or from this catch belt. The pulleys 65 and 66 of this rear catch belt 64 are likewise mounted upon the upper ends of slantingly arranged pairs

of arms extending up from the carriage 67 so that as shown in Figs. 1 and 2 the said rear catch belt inner pulleys 66 will be on the inside or to the right of the rear jaws 34 and 35, when these catch belt carriages are respectively in a spaced-apart position as shown in Figs. 1 and 2. During normal feeding operation of the fabric, these catch belts and their pulleys operate idly as it were, that is, they allow the fabric to feed over the catch belt pulleys through the power received from the driven main belts.

As best shown in Figs. 1 and 3 the two sets of catch belt carriages have their own separate platforms, 68 for the right-hand carriages carrying the catch belts 57 and platform 69 for the left-hand carriages 67 carrying the left-hand catch belts 64.

Attention is now particularly called to the fact that the right-hand catch belts 57 are not in line with the nearly oppositely disposed left-hand catch belts 64 but are offset in relation thereto and similarly that there is a like offset between the right-hand carriages 61 and their nearly oppositely disposed left-hand carriages 67. It will be further understood that each set of catch belts and carriages is separately and independently moved by reason of the carriages 61 at the right-hand half of the machine being mounted upon their laterally extending platform 68 which at opposite ends thereof is mounted in suitable slideways (not shown) supported from the opposite side rails 40.

The left-hand carriages 67 are supported upon their own laterally extending platform 69, the opposite ends of which similarly are slidingly mounted in suitable slideways (not shown) supported or let down from the opposite side rails 40 at the left hand half of the machine. The two sets of catch belts are at the proper time simultaneously moved towards each other from their retracted positions shown in Figs. 1 and 2 to their forward positions as shown in Fig. 3. In this forward position, the near pulleys of the two sets of catch belts have advanced preferably to be slightly past each other as most plainly shown in Fig. 3. Conveniently branches 85' of the air lines 85 that go to the upper ends of cylinder 53 to open the jaws 33 and 35 may also go to the outer ends of both the horizontal cylinders 70 and 71 operating the catch belts so that as the jaws are opened the piston 72 of cylinders 70 and 71 will be forced towards each other moving the two series of catch belts to the position of Fig. 3.

Correspondingly the air lines 86 that carry the compressed air to the lower ends of vertical cylinders 53 have branch lines 86' that carry the compressed air to the inner ends of the horizontal cylinders and operate to move the catch belts apart to the position shown in Fig. 1. This slightly passing movement of the catch belts it will be seen will operate to carry the forward depending end 56 of the fabric from the position shown in Fig. 2 to a position of the parts of Fig. 3 where this depending end will have been carried from its depending position up to and upon the upper rear portion of the left-hand catch belts. It will be understood that during the advancing of these catch belts to their slightly past position, the upper length of the catch belts will be each moving forwardly or to the left. After a very short time, the forward end 56 will be carried by the left-hand catch belts through the now separated rearward jaws 34 and 35 and onto the main feed belts 51 at this left-hand end of the machine. It

will be further understood that this approaching and slightly relative passing of the catch belts will be automatically brought about promptly after the tearing device has accomplished its operation and been raised to its raised position as shown in Fig. 2. The advance of the two sets of catch belts will preferably be simultaneous and may conveniently be accomplished by pneumatic means.

Such pneumatic means may conveniently consist of two sets of tandem-arranged pairs of pneumatic cylinders 70 and 71, one set arranged beneath each opposite end of the tearing zone and conveniently supported by suitable brackets (not shown) depending from the side rails of the machine. As particularly shown in Figs. 1 and 3 the right-hand cylinder 70 has its piston 72 in the outer end of said cylinder when the catch belts are in distended position and this piston 70 has a piston rod 73 reaching to the right end connected to the platform 68 which carries the carriages 61 and thereby the catch belts 57. Similarly the left-hand cylinders 71 have pistons 72 at the outer end of the cylinders 71 when the catch belts are in distended position so that the piston rod 73 therefrom extending to the left end is connected to the platform 69. It will now be apparent that on air under pressure being admitted to the farther or remote sides of said pistons, they will be moved for the length of their travel in said cylinders and thereby in obvious manner will carry the platforms 68 and 69 towards but not quite to each other and similarly the carriages 61 and 67 towards but not quite to each other, although the latter members, as already mentioned, are offset from each other.

Preferably I provide means to stop the feeding forward of the woven fabric while the fabric-holding jaws are closed. This prevents the fabric being piled up just to the right of the front or right hand pair of jaws. The means for accomplishing this stoppage of the forward feed without stopping the rotation of the main feed rollers 45 may consist of a cleat 74 carried at its opposite ends by a pair of bell crank levers 75 operated by a rod 76 connected to the bridge 68 whereby on the bridge 68 moving to the right which happens when the jaws are being closed the cleat is lowered and holds the length of fabric 23 from traveling forward with the main feed belts. In other words the fabric is held from advancing through the power driven belts continue to travel but the fabric is held from traveling with the belts causing a slippage between the fabric which simply rests of its own weight on the belts 46.

During the time of the tearing operation and until the tearing device has been raised out of the way in the tearing zone, the fabric being advanced from the feed rollers 48 and 49 piles up to the right of the cleat 74 on the stationary table 44. But on the completion of the tearing operation and the raising of the tearing device, the sequence of movement of the parts of my machine is that the catch belts advance first and then the jaws open and on the advance of the catch belts the bridge 68 moves to the left. This moves the connecting rod 76 to the left and swings the bell crank 75 clockwise and lifts the cleat 74. Thereupon the weight of the fabric resting on the belts 46 becomes operative to let the fabric feed forward with the belts 46. It will be understood that the feed of these belts is fast enough to pull all the accumulated or piled-up fabric from table 44 well before another tearing operation and its incidental stoppage of feed takes place.

The feeding forward of the long length of fabric continues until the cloth meter 52 registers the passage of the required length of fabric whereupon the meter again makes the electric contact which directly actuates the motor 37 and indirectly successively closes the two pairs of jaws, withdraws the catch belts to retracted position, drives the tearing device down to perform a complete tearing operation and raises the tearing device whereupon the catch belts are again advanced, the jaws opened and the new end of fabric fed through the left-hand jaws and the fabric again fed forward all in proper sequence and automatically performed.

It will now be seen that I have produced a machine well adapted to fulfill the purposes and to perform the operations mentioned at the beginning of this specification.

And in particular it will be seen that I have provided means for holding a short length of full width woven fabric taut while simple, direct and positively acting tearing means tears the fabric from some intermediate point clear through the opposite selvages and especially that the tearing arms are loosely mounted with enough easily swinging motion to follow between two adjacent warp threads so as to produce a straight edge for a hem at the two new ends produced by each tearing operation.

Furthermore, it will be seen that though the tearing operation has completely separated the on-coming new end of fabric from the drawing or feeding means located beyond the second pair of jaws, yet by an ingenious system of two sets of bodily moving constantly advancing "catch belts" or auxiliary feed belts, I have provided means after the tearing device is removed from the tearing zone to carry the on-coming new end of woven fabric across the tearing zone and between the second pair of now opened but recently closed fabric engaging jaws and into working engagement with the main feeding belts beyond the second pair of jaws.

What I claim as new and desire to secure by Letters Patent is:

1. In a machine for tearing full width woven fabric crosswise, the combination of two spaced pairs of holding members, the members of each pair being in moveable relation to each other and each pair when separated adapted to have a full width of the fabric proceed horizontally therebetween and adapted when closed to hold a short length of the fabric taut between the said two pairs, a tearing device located vertically from the said held length of fabric and movable vertically thereabouts and therefrom and comprising a spear point opposite an intermediate part of the said held length of fabric and two arms extending loosely therefrom in opposite directions laterally and at a slant whereby on the tearing device being moved vertically against the fabric the said spearpoint makes a short cut and said arms tear the fabric crosswise therefrom in opposite directions completely through the opposite edges thereof.

2. In a machine for tearing full width woven fabric crosswise, the combination of two spaced pairs of holding members, the members of each pair being in moveable relation to each other and each pair when separated adapted to have a full width of the fabric proceed horizontally therebetween and adapted when closed to hold a short length of the fabric taut between the said two pairs, a tearing device located above the said held length of fabric and comprising a spear point above an intermediate part of the said held length of fabric and two arms extending loosely therefrom in opposite directions laterally and at a slant, yielding means for feeding a full width length of woven fabric towards and through said first of said pairs of jaws and from the second pair of jaws, means for intermittently closing said two pairs of jaws and means for then moving said tearing device against the fabric.

said held length of fabric and comprising a spear point above an intermediate part of the said held length of fabric and two arms extending loosely therefrom in opposite directions laterally and upwardly whereby on the said tearing device descending the said spearpoint makes a short cut and said arms tear the fabric crosswise therefrom in opposite directions completely through the opposite edges thereof.

3. In a machine for tearing full width woven fabric crosswise, the combination of two spaced pairs of jaws, the members of each pair being in moveable relation to each other and each pair when separated adapted to have a full width of the fabric proceed horizontally therebetween and adapted when closed to hold a short length of the fabric taut between the said two pairs, a tearing device located vertically from the said held length of fabric and movable vertically thereabouts and therefrom and comprising a spear point opposite an intermediate part of the said held length of fabric and two arms extending loosely therefrom in opposite directions laterally and at a slant, yielding means for feeding a full width length of woven fabric towards and through said first of said pairs of jaws and from the second pair of jaws, means for intermittently closing said two pairs of jaws and means for then moving said tearing device against the fabric and then therefrom.

4. In a machine for tearing full width woven fabric crosswise, the combination of two spaced pairs of jaws, the members of each pair being in moveable relation to each other and each pair when separated adapted to have a full width of the fabric proceed horizontally therebetween and adapted when closed to hold a short length of the fabric taut between the said two pairs, a tearing device located above the said held length of fabric and comprising a spear point above an intermediate part of the said held length of fabric and two arms extending loosely therefrom in opposite directions laterally and upwardly, yielding means for feeding a full width length of woven fabric towards and through said first of said pairs of jaws and from the second pair of jaws, means for intermittently closing said two pairs of jaws and means for then moving said tearing device downwardly and then upwardly.

5. In a machine for tearing full width woven fabric crosswise, the combination of two spaced pairs of jaws, the members of each pair being in moveable relation to each other and each pair when separated adapted to have a full width of the fabric proceed horizontally therebetween and adapted when closed to hold a short length of the fabric taut between the said two pairs, a tearing device located vertically from the said held length of fabric and movable vertically thereabouts and therefrom and comprising a spear point opposite an intermediate part of the said held length of fabric and two arms extending loosely therefrom in opposite directions laterally and at a slant, yielding means for feeding a full width length of woven fabric towards and through said first of said pairs of jaws and from the second pair of jaws, means for intermittently closing said two pairs of jaws and means for then moving said tearing device against the fabric and then therefrom and means for arresting the feeding forward of the fabric to the first pair of jaws on the closing of said jaws.

6. In a machine for tearing full width woven fabric crosswise, the combination of two spaced pairs of jaws, the members of each pair being in

moveable relation to each other and each pair when separated adapted to have a full width of the fabric proceed horizontally therebetween and adapted when closed to hold a short length of the fabric taut between the said two pairs, a tearing device located vertically from the said held length of fabric and movable vertically theretowards and therefrom and comprising a spear point opposite an intermediate part of the said held length of fabric and two arms extending loosely therefrom in opposite directions laterally and at a slant, yielding means for feeding a full width length of woven fabric towards and through said first of said pairs of jaws and from the second pair of jaws, means for closing said two pairs of jaws, means for then moving said tearing device against the fabric and then therefrom, means operative after each tearing operation and after the withdrawal of the tearing device for opening both pairs of jaws and auxiliary feeding means means operative after each tearing operation and the withdrawal of the tearing device for carrying the new end of the fabric forward from the first pair of jaws, to, through and from the second pair of jaws.

7. In a machine for tearing full width woven fabric crosswise, the combination of two spaced pairs of jaws, the members of each pair being in moveable relation to each other and each pair when separated adapted to have a full width of the fabric proceed horizontally therebetween and adapted when closed to hold a short length of the fabric taut between the said two pairs, a tearing device located vertically from the said held length of fabric and movable vertically theretowards and therefrom and comprising a spear point opposite an intermediate part of the said held length of fabric and two arms extending loosely therefrom in opposite directions laterally and at a slant, yielding means for feeding a full width length of woven fabric towards and through said first of said pairs of jaws and from the second pair of jaws, means for intermittently closing said two pairs of jaws and means for then moving said tearing device against the fabric and then therefrom and means for arresting the feeding forward of the fabric to the first pair of jaws on the closing of said jaws, means operative after each tearing operation and after the withdrawal of the tearing device for opening both pairs of jaws and auxiliary feeding means advanced into the tearing zone after each tearing operation and the withdrawal of the tearing device for carrying the new end of the fabric forward from the first pair of jaws, to, through and from the second pair of jaws and into engagement with the regular feeding means beyond the said jaws and means for withdrawing the auxiliary feeding means from the tearing zone before the next tearing operation.

8. In a machine for tearing full width woven fabric crosswise, the combination of two longitudinally spaced sets of belts for normally yielding feeding said fabric forward, spaced means for intermittently holding a short length of said fabric taut in the tearing zone therebetween, a wedge-shaped tearing device located above the said held length of fabric and having a puncturing point above an intermediate part of said held length of fabric and two arms extending loosely therefrom laterally and upwardly, means operative when the short length of fabric is held taut for moving said tearing device downwardly until said arms tear completely through said fabric and then lifting the tearing device out of the

tearing zone, auxiliary feeding means bodily movable to extend across the tearing zone for advancing the new torn end through said holding means and into engagement with the normal feeding means located beyond the second-reached holding means for again feeding the fabric forward and means for removing said auxiliary feeding means from the tearing zone before the tearing device is brought into another operation.

9. In a machine for tearing full width woven fabric crosswise, the combination of two spaced pairs of jaws, the members of each pair being in movable relation to each other and each pair when separated adapted to have a full width of the fabric proceed horizontally therebetween and adapted when both pairs are closed to hold a short length of the fabric taut therebetween in a tearing zone, a tearing device located vertically from said held length of fabric and movable vertically theretowards and therefrom and including a spear point opposite an intermediate part of said held length of fabric and two arms extending therefrom in opposite directions laterally and at a slant whereby on the tearing device being advanced the said point makes a short cut transversely and said arms tear therefrom completely across the full width of fabric.

10. In a machine for tearing full width woven fabric crosswise, the combination of two spaced pairs of jaws, the members of each pair being in movable relation to each other and each pair when separated adapted to have a full width of the fabric proceed horizontally therebetween and adapted when both pairs are closed to hold a short length of the fabric taut therebetween in a tearing zone, a tearing device located vertically from said held length of fabric and movable vertically theretowards and therefrom and including a spear point opposite an intermediate part of said held length of fabric and two arms extending therefrom in opposite directions laterally and at a slant whereby on the tearing device being advanced the said point makes a short cut transversely and said arms tear therefrom completely across the full width of fabric, two sets of regular feed belts, one feeding the fabric to the first pair of jaws and the other taking the fabric from the second pair of jaws, two sets of auxiliary feed belts each overlapping one of the regular sets of feed belts and having its carrying length extending through the adjacent pairs of jaws, each of said auxiliary sets of feed belts being carried on spaced pairs of pulleys one of each pair within and one without the tearing zone and mounted for bodily movement of its set towards and from the said tearing zone whereby on the auxiliary sets of feed belts being retracted the said tearing device may be temporarily moved into the tearing zone and when the tearing device has been operated and withdrawn leaving a new depending end of the on-coming fabric between the pairs of jaws, the auxiliary feed belts may be temporarily advanced into the tearing zone into interlapping relation and will carry the new on-coming end of fabric through the second pair of jaws and into operative engagement with the regular delivery feed belts beyond the second pair of jaws.

11. In a machine for tearing full width woven fabric crosswise, the combination of two spaced pairs of jaws, the members of each pair being in movable relation to each other and each pair when separated adapted to have a full width of the fabric proceed horizontally therebetween and adapted when both pairs are closed to hold a

short length of the fabric taut therebetween in a tearing zone, a tearing device located vertically from said held length of fabric and movable vertically theretowards and therefrom and including a spear point opposite an intermediate part of said held length of fabric and two arms extending therefrom in opposite directions laterally and at a slant whereby on the tearing device being advanced the said point makes a short cut transversely and said arms tear therefrom completely across the full width of fabric, means for feeding the desired length of fabric to the

tearing zone, means for withdrawing the auxiliary feed belts from the tearing zone and closing the said jaws, means for then moving the tearing device into and out of operating position, means for then advancing the auxiliary feed belts into the tearing zone and feeding the on-coming end through the second jaws and opening the said jaws and feeding the on-coming end through the second jaws to the rear main feeding means and resuming the regular feeding from the main feed belts.

MAYNARD W. HIGBY.
